(57) **CLAIM**

The ornamental design for an automotive wheel, as shown and described.

DESCRIPTION

FIG. 1 is a perspective view of an automotive wheel embodying my new design.

FIG. 2 is another perspective view thereof; and

FIG. 3 is a front view thereof.

FIG. 4 is a perspective view of an automotive wheel embodying my new design, according to a second embodiment;

FIG. 5 is another perspective view thereof; and

FIG. 6 is a front view thereof.

FIG. 7 is a perspective view of an automotive wheel embodying my new design, according to a third embodiment;

FIG. 8 is another perspective view thereof; and

FIG. 9 is a front view thereof.

FIG. 10 is a perspective view of an automotive wheel embodying my new design, according to a fourth embodiment;

FIG. 11 is another perspective view thereof; and

FIG. 12 is a front view thereof.

FIG. 13 is a perspective view of an automotive wheel embodying my new design, according to a fifth embodiment;

FIG. 14 is another perspective view thereof; and

FIG. 15 is a front view thereof.

FIG. 16 is a perspective view of an automotive wheel embodying my new design, according to a sixth embodiment;

FIG. 17 is another perspective view thereof; and

FIG. 18 is a front view thereof; and,

FIG. 19 is a side view of the automotive wheel in FIGS. 1-18.
